Des. 233,625

Patented Nov. 12, 1974

233,625

FLUID PRESSURE TESTING APPARATUS

Gary R. Bluem, 7980 Wynnwood Road,
Minneapolis, Minn. 55427

Filed June 4, 1973, Ser. No. 366,487

Term of patent 14 years

Int. Cl. D10—04

U.S. Cl. D52—6 R

FIG. 2

FIG. 5

FIG. 1

FIG. 4

FIG. 3

FIG. 6

FIG. 1 is a representative side elevational view of a fluid pressure testing apparatus showing my new design; FIG. 2 is a top plan view thereof;

FIG. 3 is a bottom plan view thereof;

FIG. 4 is a representative side elevational view of a modified form of my new design of FIG. 1;

FIG. 5 is a top plan view of FIG. 4; and

FIG. 6 is a bottom plan view of FIG. 4.

I claim:

The ornamental design for a fluid pressure testing apparatus, substantially as shown and described.
